UNITED STATES PATENT OFFICE

HILAND R. FARNSWORTH, OF SANDUSKY, OHIO, ASSIGNOR TO THE PAPER & TEXTILE MACHINERY COMPANY, OF SANDUSKY, OHIO

SUCTION BOX LEVER FOR SUCTION ROLLS

Application filed March 26, 1928. Serial No. 264,637.

The present invention relates to a wire replacement means for suction rolls and more particularly to a leverage device directly applicable to the roll.

5 Heretofore it has been the general practice to use a device known in the trade as a "tooth pick" and adapted to be inserted into the suction roll shell from end opposite to that through which the suction is taken. This "tooth pick" is a rod or bar of considerable length and simply gives a lifting purchase at that end of the shell and removed beyond that end a distance somewhat greater than the width of wire to be used in replacement. 10 Thus, in the more general practice, the upper bearing sections at that end are removed sufficiently to enable the lifting of that end of the shell sufficiently to enable the wire to be slipped laterally between the lower bearing 15 and adjacent shell wall, the looped wire is then brought opposite that end of the roll, the "tooth pick" is then slid through the wire loop and sufficiently into the shell to give the necessary purchase for lifting. A hoist of any desired type is then applied to the projecting or free end of the "tooth pick". A block and tackle, jack, or other means of well known construction and operation is then applied to lever that end of the roll upwardly. 20 In this construction the opposite end suction roll bearing becomes the fulcrum as will be readily understood, only a very slight fulcrum action is possible. Swinging movement beyond that point immediately wrecks some of the apparatus. Practically always the damage, and it is very costly damage, results at or in the neighborhood of the fulcrum, where practically the entire strain is centred. It will be understood, of course, 25 that only a very slight lift of the free end of the roll is necessary. Likewise it is obvious that, because of the great weight being handled a powerful hoisting apparatus is necessary. Such apparatus, of course, must be instantly stopped at the right point. The slightest excess lift beyond that point instantly wrecks the parts at the fulcrum end, as previously stated. As soon as the roll end 30 has been lifted, the wire is slipped laterally from the "tooth pick" over the shell, the shell

lowered, and the "tooth pick" withdrawn. Many forms of these "tooth picks" have been devised and a considerable number patented. In all there is the same difficulty in their use—damage at fulcrum end. 55

More recently an attempt has been made to operate from the opposite end by reducing the shell end and extending it beyond its bearing to act as a lever having a fulcrum at the bearing, the bearing being specially constructed as a sliding fulcrum to permit both a slight sliding and pivot motion of the shell, simultaneously. I refer to the patent to E. E. Berry 1,602,875 dated October 12, 1926, reissued as 16,848 January 10, 1928. In this construction there is a tremendous strain, the entire weight of the whole assembled roll on a small diameter elongated tube. A special construction sliding rocker bearing must be resorted to with this construction to accommodate the pivotal swing of the shell. 60 65 70

The construction and disposition of the various parts of this invention have been so devised and designed as to overcome the objections above noted, while at the same time 75 providing a simple, compact efficient and economical construction with the least possible variation or modification of any of the parts. In fact, the only actual change in construction, if such may logically be called a 80 change, is the extension of the suction box at one end to provide the lever.

In order to more clearly disclose the construction, operation and use of the invention reference should be had to the accompanying 85 drawings forming part of the present application. Throughout the several figures of the drawings like reference characters designate the same parts in the several views.

In the drawings:

Fig. 1 is a central vertical longitudinal cross section through the roll;

Fig. 2 is a side elevation showing bearing carriage removed, and, in dotted line position, assembled. 95

Fig. 3 is a lateral cross section on line 3—3 of Fig. 1, looking in the direction of the arrows.

Fig. 4 is a left hand end view of Fig. 1.

Fig. 5 is a fragmentary cross section of 100

the left hand end of Fig. 1 with supporting carriage and box removed to show lugs of head.

Fig. 6 is a fragmentary vertical cross section of the right hand end of the roll, showing a modified form; and

Fig. 7 is an end elevation showing a modified form of fulcrum.

According to the present invention the leverage is applied indirectly to the shell, as a direct lift instead of as a lever. The leverage is applied directly to the suction box and, through it, as a lift to the shell at its free end. The shell 1 is of well known construction and of the same diameter throughout. The heads 9 and 10 for supporting the suction box, and the adjustable mounting of the box ends within the heads, as well as the guide rails and rollers for inserting and running the box are of well known construction and need not be described in detail in the present application as they do not enter into this particular invention, particularly as to the general features of such constructions.

The suction box 2 extending longitudinally through the roll is socketed at its suction end to receive a suction tube or strong pipe 3 which is extended considerably beyond the roll end and through a yoke 4 and then coupled in any suitable manner to the piping of the suction line. At a point between the shell end and yoke 4 a fulcrum post or block 5 is provided. This post is made fast either to a frame member of the machine, the floor, or some other solid support capable of adequately sustaining the weight imposed. As shown in the drawings, particularly Fig. 1, the upper surface of the fulcrum just contacts with the cooperating under face of suction tube 3, at that point, there being no appreciable weight or pressure on the fulcrum. Suction tube 3 is, of course, in effect, an extension of suction box 2. If made in one piece with box 2 as an elongation of it, the construction would be substantially the same and the operation and results obtained would be the same as in the exact construction shown in Fig. 1, where the box and tube are separate but firmly connected, one within the other. Directly above the tube 3, where it passes through yoke 4, is a pressure screw 6 which is threaded through the yoke and into contact with the upper end of the tube to force that outer end vertically downward in yoke 4. As will be seen on reference to Fig. 1 the opening through yoke 4 is sufficiently elongated, vertically to permit ample downward movement or depression of the outer end of suction tube 3. Since the tube is in contact with the top of the fulcrum post the opposite end of the suction box will be levered upwardly. As it moved upwardly it will carry the head 10 at that end upwardly. The first slight upward movement will bring the outer edges or shoulders of the inwardly ex-

tending guide lugs 7 which are formed integral with the rim 11 on the suction box 2 into engagement with the inner shell wall and the continued upward movement beyond that point will carry the shell end upwardly with the box. It will be seen that there is no great strain on the shell any where as a result of this method of lifting. In fact the lifting strain is practically identically the same as the normal strain of supporting the shell by its rollers at each end. It will also be clear that the tube 3 has perfect freedom of movement radially in its guides in the corresponding head, toward and from the inner wall of the shell with no danger of being cramped against or engaged by the shell before the outer end of the tube 3 reaches its lower most position. As will be readily understood, the necessary amount of lift of the shell end is very slight—only enough to permit sliding out of its support so that it may remain freely suspended for slipping on of the wire. In this instance the support comprises the usual roller bearings carried by a cradle which, in turn is mounted in a suitable housing. This housing is provided with a set of rollers which may be swung into or out of engagement with the floor by a hand lever and suitable connections of well known type and as clearly shown in Figs. 1 and 2. When the roll end has been partially raised, as above described, this set of rollers will be depressed, thereby putting the housing on wheels. Then the housing will be run out from under the roll, leaving it suspended on the suction box.

It will be noticed that the fulcrum post is convex in cross section longitudinally relatively to the length of the suction tube resting thereon and concave in cross section laterally relatively thereto. Thus, upwardly extending side members or wings are provided at the sides of the tube to hold it against lateral slipping while a rounded fulcrum surface is provided across which the tube is free to rock between such wings.

As a modification and to permit slightly greater flexibility or wider range of lift to the free end of the shell, the frame and base for supporting the roller bearings at the suction end may be pivotally connected together by a pin 12 extending laterally or at right angles to the length of the roll. Thus, when the free end is lifted if it passes what would otherwise be the danger point, the pivot will prevent cramping of the bearings and breaking of the frame. It is obvious, too, that the vertical opening through the yoke 4 below the tube 3 may be correspondingly increased to accommodate such further downward swing of that end of the tube. This pivot arrangement is shown in Fig. 6.

As a modified, though not preferred, form of fulcrum, a longitudinally concaved roller 8 may be substituted for the fulcrum post.

This roller is journaled in a suitable bracket which may be bolted or similarly secured in place of the fulcrum post 5.

It is thought that the construction, operation and use of the invention will be clearly understood from the preceding detailed description wherein a preferred form has been shown by way of illustration. It is not intended to limit the invention to the exact construction illustrated. Many changes may be made in the construction, arrangement and disposition of the various parts, within the scope of the appended claims, without departing from the field of the invention and it is meant to include all such within this application wherein only illustrative constructions have been disclosed for a clearer explanation.

Having described my invention, what I claim and desire to protect by Letters Patent 20 is:

1. In a suction roll, a revolvably mounted shell, a suction box therein, and means acting upon one end of said box to cause said box to engage and lift the opposite end of said shell.

2. In a suction roll, a revolvably mounted shell, a suction box therein, means acting upon one end of said box to cause said box to engage and lift the opposite end of said shell and means for maintaining said box in such engagement.

3. In a suction roll, a revolvably mounted shell, a suction box therein and extending therebeyond, and means acting upon said extended portion to cause said box to engage and lift the opposite end of said shell.

4. In a suction roll, a revolvably mounted shell, a suction box therein, a fulcrum adapted to engage said box, and means for moving said box on said fulcrum to cause it to engage and lift one end of said shell.

5. In a suction roll, a revolvably mounted shell, a suction box therein, a fulcrum disposed beneath said box, and pressure means operating upon said box to cause it to swing on said fulcrum to engage and lift one end of said shell.

6. In a suction roll, a revolvably mounted shell, a suction box therein and extended therebeyond, a fulcrum disposed beneath said suction box extension, and pressure means operable upon the extended end to depress it and swing the opposite end upwardly into lifting engagement with said shell.

55 7. In a suction roll, a revolvably mounted shell, a suction box therein and extended therebeyond, a fulcrum disposed beneath said suction box extension, a yoke surrounding said extension, and means carried by said yoke for adjusting said extension vertically within said yoke to cause lifting engagement between the opposite end of said suction box and the corresponding shell end.

8. In a suction roll, a revolvably mounted shell, a fulcrum spaced from one end of said

shell, a yoke spaced from said fulcrum in the same direction relatively to the shell, a suction box within said shell and provided with an extension lying across said fulcrum and projecting through said yoke, and means carried by said yoke and adapted to engage said extension to rock the same on its fulcrum and cause lifting engagement between an end of said box and said shell.

9. In a suction roll, a shell, a movably mounted suction box therein and adapted to support said shell when the shell is in inoperative position and means for supporting said box.

10. In a suction roll, a shell, a suction box mounted therein and adapted to maintain said shell in suspended overhung position relatively to one end of said roll, when the shell is in inoperative position and means for supporting said box.

11. In a suction roll, a shell, a suction box therein and adapted to engage the inner wall of said shell to thereby support said shell, and means causing such engagement.

12. In a suction roll, a shell, and a suction box therein, one of said parts having swinging movement toward the other.

13. In a suction roll, a shell, and a suction box therein, one of said parts having swinging movement toward the other and about a point in proximity to one end of said shell.

14. In a suction roll, a shell, a suction box therein, said box having swinging movement toward said shell to support said shell.

15. In a suction roll, a shell, a suction box therein, said box having swinging movement toward said shell to support said shell and means for adjusting such swinging movement.

16. In a suction roll, a shell, a suction box mounted therein and extending therebeyond, a support upon which said box rests and means for causing said box to swing on said support.

Signed at Sandusky, Ohio, this 23rd day of March, 1928.
